UNITED STATES PATENT OFFICE.

JOHN B. TURBEVILLE AND MARION F. HIGGS, OF LINGLEVILLE, TEXAS.

WASHING-MACHINE.

SPECIFICATION forming part of Letters Patent No. 601,740, dated April 5, 1898.

Application filed October 17, 1896. Serial No. 566,028. (No model.)

To all whom it may concern:

Be it known that we, JOHN B. TURBEVILLE and MARION F. HIGGS, citizens of the United States, residing at Lingleville, in the county 5 of Erath, State of Texas, have invented certain new and useful Improvements in Washing-Machines, of which the following is a specification, reference being had therein to the accompanying drawings.

10 This invention relates to certain new and useful improvements in washing-machines; and it has for its object, among others, to provide a simple and cheap portable machine combining a washer and a boiler with means 15 for regulating the tension of the rollers one upon the other, so as to prevent injury to the clothes, the tearing off of buttons, and the like.

The device embodies a light stand, upon which is removably supported the boiler, having 20 a depending tank or receptacle connected with the boiler or tub proper by pipes, which serve, further, to aid in supporting the said receptacle, and the whole adapted to be mounted upon the support over a suitable heat. The 25 rollers are mounted upon a suitable framework having clamps or analogous devices for engaging the sides of the tub to hold it rigidly yet removably in position, and the device as a whole is simple, cheap, durable, and most 30 efficient for the purposes for which it is designed.

Other objects and advantages of the invention will hereinafter appear, and the novel features thereof will be particularly pointed 35 out in the appended claims.

The invention is clearly illustrated in the accompanying drawings, which, with the letters of reference marked thereon, form a part of this specification, and in which—

40 Figure 1 is a perspective view of the machine complete. Fig. 2 is a substantially central vertical section through the same. Fig. 3 is a vertical cross-section through the rollers and their support.

45 Like letters of reference indicate like parts throughout the several views.

Referring now to the details of the drawings by letter, A designates a suitable stand or support, made preferably of wire, of sufficient strength to support the operating part 50 and of the required height to provide room

for a heater (not shown) beneath the depending receptacle of the washer.

B designates a tub or boiler having a central opening b in its bottom, and the walls being tapered, as seen in Figs. 1 and 2. This tub may be of any desired capacity, and depending from the bottom thereof is the vessel or receptacle C, which is preferably in the shape of a cone with its apex terminating at 60 the said opening b in the bottom of the tub. This receptacle is provided with a suitable faucet D, as seen in Fig. 1, and pipes E are provided, there being in this instance three, which afford communication between the 65 lower portion of the receptacle C and the tub B and serve, further, to strengthen the connection between these two parts, as will be readily understood.

F is a plate, from near the opposite ends of 70 which extend the vertical plates F', the upper ends of which are bifurcated or slotted, as seen at f in Figs. 1 and 2, and in these slots is journaled the shaft G, carrying the large corrugated roller H, one end of the shaft being 75 provided with a crank and handle H', as seen in Figs. 1 and 2, by which it may be operated. I are springs connected at one end to the ends of this shaft and their other ends extended through the plate F, as seen in Fig. 80 2, and provided with thumb-nuts i, by means of which the tension of the springs may be adjusted.

J are small corrugated rollers arranged on a lower plane and upon opposite sides of 85 the axis of the roller H, as seen best in Fig. 3, and beneath these corrugated rollers and having their axes arranged inside of those of the rollers J are rollers K, the shafts of the rollers J and K being mounted in the vertical 90 plates F', as seen in Figs. 2 and 3.

The plate F, with its rollers and their attachments, is detachably supported within the tub B by means of the metallic plates L, which are secured to the under side of opposite ends of the plate F, as seen best in Fig. 2, and extended upwardly and outwardly in a plane substantially parallel with the inclined walls of the tub and their free ends bent outward and downward, as seen in Figs. 95 1 and 2.

In practice the plate F, with its accessories,

is placed in position within the tub and supported at the proper distance from the bottom thereof by means of the bends of the plates L resting upon the upper edge of the tub, as clearly shown in Figs. 1 and 2. Water is placed in the receptacle C, and a lamp, gas-stove, or other heater (not shown) placed beneath the same, and as the water is heated the steam and water is forced up through the pipes E into the tub, which may contain a sufficient quantity of water, and the clothes therein will be thoroughly and quickly cleansed. The cone-shaped boiler has been found from practice to produce the best results, the water therein being more easily heated, the facilities for heating being better, and the steam more readily forced therefrom as the water is heated. The clothes can be washed and boiled in the same tub, thereby saving the changing and lifting, and the water can be drawn from the same through the faucet and conducted away, if desired, by hose.

What we claim as new is—

1. The combination with a tub, having inclined sides, of a plate carrying a series of

rollers, and metallic plates secured to opposite ends of the said plate, and having their outer ends bent to engage over the upper edge of the tub, with the portions within the tub inclined to conform to the inclination of the walls of said tub; substantially as described.

2. The combination with a tub having inclined walls, of a plate carrying a series of rollers and the metallic plates secured at one end to the under side of said plate at the ends each of said metallic plates having an inclined portion to conform to, and bear against, the inner surface of the inclined walls of the tub, and their other ends bent downward and outward forming a loop resting upon the upper edge of said tub, substantially as herein shown and described.

In testimony whereof we affix our signatures in presence of two witnesses.

JOHN B. TURBEVILLE.
MARION F. HIGGS.
